UNITED STATES PATENT OFFICE.

WILLIAM L. MONROE AND ISAAC N. SIMPSON, OF OMAHA, NEBRASKA.

DESIGN FOR A WASHING-MACHINE HUB.

SPECIFICATION forming part of Design No. 35,147, dated October 1, 1901.

Application filed July 1, 1901. Serial No. 66,788. Term of patent 14 years.

To all whom it may concern:

Be it known that we, WILLIAM L. MONROE and ISAAC N. SIMPSON, citizens of the United States, residing at Omaha, in the county of Douglas and State of Nebraska, have invented and produced a new and original Design for Washing-Machine Hubs; and we do declare the following to be a full, clear, and exact description of the same, reference being had to the accompanying drawings, forming a part thereof.

This invention relates to a new and peculiarly shaped hub to be used in conjunction with washing-machine shafts.

15 In the accompanying drawings we have shown in Figure 1 a perspective view of a washing-machine hub embodying our invention, while Fig. 2 shows a top view thereof.

In referring to the drawings it will be noticed that our invention relates to a peculiarly constructed and shaped hub and comprises the hub 5 5', which is cast hollow, and from which hub extend the two counterpart circular portions or members 4 and 4', which 25 members are united by the vertical portion 8 at one point, so that these members or portions 4 and 4' are united as shown. Extending a little more than half-way around the hub 5 5' is the projecting elongated cam portion 6, which extends outward as far as the circular members 4 and 4'. Extending from these circular portions 4 and 4' are the hol-

low neck portions 3 and 3', which neck portions are terminated by the rings or circular projections 2 and 2', as clearly shown in Fig. 35 1. Interiorly these neck portions 3 3' are provided with the inwardly-extending ribs b b, as clearly shown.

In referring to the drawings it will be noticed that by virtue of the circular members 40 or portions 4 and 4', the vertical connecting portion 8, and the projecting cam portion 6 a continuous runway or groove is provided, as shown. Projecting from this cam portion 6 are a plurality of projecting pins a, which 45 pins support the rollers 9, as shown. It will be noticed that these rollers 9 are approximately in the form of truncated cones. In referring to Fig. 2 it will be noticed that these rollers extend a little more than half-way 50 around the hub.

Having thus described our said invention, what we claim as new, and desire to secure by United States Letters Patent, is—

The design for a washing-machine hub, as 55 herein shown and described.

In testimony whereof we affix our signatures in presence of two witnesses.

WILLIAM L. MONROE.
ISAAC N. SIMPSON.
